SPINDLE BUMPER AND IMPACT NOSE
THEREFOR

David A. Ahlstrand, Atlanta, Ga.

Application August 18, 1951, Serial No. 242,553

6 Claims. (Cl. 139—166)

1

The invention relates to an improvement in spindle bumpers for textile machinery, and has for one purpose to provide a spindle bumper of increased life and efficiency.

Another purpose is to provide a spindle bumper in which breaking under wear is reduced to a minimum.

Another purpose is to provide a spindle bumper in which relatively small pieces of inexpensive material may be employed.

Another purpose is to provide a spindle bumper in which, upon breakage or wear, only part of the spindle bumper structure need be replaced.

Another purpose is to provide a spindle bumper, the cost of which is substantially reduced in relation to the spindle bumpers in current use.

Another purpose is to provide a spindle bumper which may be formed of a wide variety of material, including plastics, textiles, rubber and rubber substitutes, in a variety of combinations.

Another purpose is to provide an improved impact nose for spindle bumpers which has maximum life and wear and impact-resisting characteristics.

Other purposes will appear from time to time in the course of the specification and claims.

The present application is a continuation-in-part of my copending application Serial No. 185,886, filed September 20, 1950, for "Spindle Bumpers."

I illustrate my invention more or less diagrammatically in the accompanying drawings wherein:

Figure 1 is a side elevation of one embodiment of my invention;

Figure 2 is a side elevation of another embodiment of my invention;

Figure 3 is a side elevation of a third embodiment of my invention;

Figure 4 is a side elevation of a fourth embodiment of my invention;

Figure 5 is a side elevation of a fifth embodiment of my invention; and

Figure 6 is an end elevation of the structure shown in Figure 5.

Like parts are indicated by like symbols throughout the specification and drawings.

Since I do not claim any novelty in the mechanism on which the spindle bumper is used, I illustrate herein only the spindle bumper structure itself.

Referring to the drawings, 1 indicates an applicator. The applicator has for its purpose to apply the bumper structure to the spindle itself. The applicator may be made of any suitable material, preferably of a cheap material, so that,

2

if desired, the applicator may be thrown away after use. It enables the bumper structure to be easily applied to the spindle. The spindle is not herein shown, but the applicator can be taken as typical of a rod or spindle structure upon which the bumper is positioned during use. In application, the conic recess 2 of the applicator 1 is placed over the conic end of the machine shaft, and the straps are pushed off of the applicator shaft and onto the machine shaft. On the spindle, the bumper parts are positioned as shown on the applicator in the drawings herein.

It will be understood that the bumper, when used in textile weaving, absorbs the shock which, in machines now available, is absorbed by a unitary strap formed in a plurality of bends. In the use of the forms of my invention, in Figures 1 and 2, no piece of material is subjected to more than one bend. Taking, for example, the form of Figure 1, I provide a plurality of relatively short straps 3, each of which is bent to form a U, having, in its opposite arms, apertures 3a and 3b. These apertures are of sufficient size to permit the U-shaped bent straps 3 to be applied readily to the applicator 1, being passed over its tapered end 1a. I find it advantageous, in the members 3, to employ pieces or straps which, if desired, may be arranged in multiple plies. I illustrate, in Figure 1, the separate plies 3 and 3c, but, if desired, more than two plies may be employed, depending upon the material used. The plies may be connected by cementing, by sewing, or by any other suitable means, or, if desired, the plies may be left uncoated. I may employ multiple plies of any suitable plastic, including, but not limited to "nylon." I may employ rubber, or any suitable rubber substitute. Under some circumstances, it may be advantageous to employ leather, either alone or in connection with a ply or plies of rubber or some other substance. In the present application I emphasize, primarily, the form rather than the substance of the various pieces employed.

In the form of Figure 1, I illustrate, for example, five U-bent short pieces or straps arranged in interpenetrating relationship, with the arms of the U's at one side of the applicator 1 entering the folds of the U's at the opposite side of the applicator. Where three of the U's are employed, as in Figure 1, I maintain the individual straps or parts properly positioned by using any suitable intermediate blocks or bits 4 within the folds of the end members of the series of U's. Each such block 4 may be made rectangular, or 55 of any other suitable form, and may be apertured,

as at 4a, to be readily applied to the applicator. The parts are so dimensioned, when rectangularly formed, that the blocks 4 may be held against rotation by the adjacent bends of the U. I may also employ any suitable end blocks or washers 5, 5, with the apertures 5a.

The form of Figure 1 merely illustrates one satisfactory arrangement. In Figure 2, the individual U-shaped strap elements formed of the plies 6 and 6a are shown with their arms arranged in abutting relationship. I may find it advantageous to provide one or more intermediate or inner blocks or washers 7 within the bend of each U. I also illustrate the terminal blocks or washers 8, as in the case of the form of Figure 1.

In the form of Figure 3, for the U-shaped members or short straps, I provide loops 10 each having overlapping ends 10a and 10b. I diagrammatically indicates, at 10c, any suitable additional ply or plies which may be employed. 11 indicate inner blocks or spacers, and 12 indicate end members or spacers. Any suitable number of spacers may be used.

In the form of Figure 4, I illustrate straps bent, in effect, to form reverse U's. Each such strap 14 is formed with loops 14b and 14c. 14a diagrammatically indicates any suitable additional ply or plies. Each such member is apertured at three points, as at 14d, 14e and 14f, to permit the passage of the applicator 1. The straps are then positioned in interfitting arrangement, as shown in Figure 4, with the free end of each strap entering the bend of an adjacent strap. At the end bends, spacers 15 may be used. 16 indicate the end spacers.

In the form of Figures 5 and 6 the applicator 1, with its tapered end 1a and its opposite end recess 2, is used as in the other forms. I provide, however, an impact nose which effects a transfer or distribution of energy when struck. In the form of Figures 5 and 6 I illustrate the general arrangement of interpenetrating U's or loops. These loops may be simple or compound. I illustrate, for example, three aligned loops, each one of which is formed by an inner member 20 and an outer member 21. While, under some circumstances, the individual elements might be connected or cemented or stapled, this is not necessary, and, as shown in Figure 5, I illustrate them as abutting but not as secured together otherwise than by their common alignment on or penetration by the applicator 1. It will be understood, of course, that each one of the loop elements and of the below described washers is appropriately apertured to permit the passage of the applicator or spindle therethrough. While I may employ a variety of material, I illustrate the inner loop elements 20 as formed of rubber or a rubber substitute, with embedded textile layers. The outer elements 21 are shown as of leather. The open ends of the loops interpenetrate with the ends of an opposite series of two loops similarly formed of inner member 25 and outer members 26. If desired, I may employ washers 27 wherever necessary.

I provide an impact receiving nose which may advantageously, but not necessarily, be formed of a different material than the rest of the structure. I illustrate, for example, a strip 30 of chrome leather. This strip begins at a point 31 in Figure 5, and is looped about itself to form a closed loop shown as from two to three layers thick. The final layer, as at 32, abuts the adjacent end of one of the above-mentioned loops 75

formed of elements 25 and 26, and enters the open bend of one of the loops formed by the members 20 and 21. If necessary, I may position, within the member 30, one or more washers 35.

The structure as shown provides a continuous overlap with no stitching or rivets. Under many circumstances, this is advantageous, but it is, nonetheless, possible to stitch or rivet the folds together, or to cement them. In any event, I form an end unit or impact nose portion, generally indicated as A in Figures 5 and 6, which is a single or complete unit, and which is a unit which does not break down into separate parts. This impact nose portion serves as a wiper, preventing lubricating oils from working back along the spindle into the body of the bumper as a whole. It keeps oil back on the spindle. But its basic purpose is to serve as a damper, to receive a traveling mass which may move at a rate as high as ninety miles per hour, and to bring it to a full stop with no bounce back. This function the nose, in connection with the rest of the bumper, performs ideally, with a minimum of wear and with great length of life.

It will be realized that whereas I have described and claimed a practical and operative device, nevertheless many changes may be made in size, shape, number and disposition of parts, and in materials used, without departing from the spirit of my invention. I therefore wish my description and drawings to be taken as in a broad sense illustrative or diagrammatic rather than as limiting me to my precise disclosure herein.

The use and operation of my invention are as follows:

In current weaving equipment it is customary to use spindle bumpers formed of a single piece. These pieces are hard to apply to the spindles, and break easily at the radius of the individual bends.

In the use of my invention I provide a structure which efficiently absorbs the shocks which the spindle bumper has to absorb. In all of the embodiments illustrated, each individual piece or bumper strap is formed with an intermediate curvilinear portion and two end portions. My design maintains the radius of each piece and prevents a break in the radius. The radius is maintained by the interposition of the free ends of adjacent pieces, and, where necessary, by the insertion of spacers such as are shown in the various figures. This maintenance of radius assures continuation of the compression effect of the bent pieces. The use of short pieces in place of the former one-piece element simplifies the replacement of worn or broken pieces. The form of Figure 1 has the advantage of reducing to a minimum the spacers, which are used in greater numbers in the form of Figures 2 and 3. In other words, the interpenetrating ends of the U's in the form of Figures 1, 4, 5 and 6 themselves constitute spacers and reduce the necessity for using intermediate spacers.

It will be realized that I may employ multi-ply elements or pieces. In use, the bumper structure, as a whole, is supplied to the user on an applicator in which the individual parts are positioned as they will be positioned on the spindle. The applicator is aligned with the spindle, and the parts are easily slid from the applicator upon the spindle. By using a relatively large number of small parts I find it simple and easy to move the parts from the applicator to the spindle, and to position them properly on the spindle. A min-

imum of force has to be applied, force entirely insufficient to damage the bumper.

The materials employed may be widely varied. I may employ a wide variety of suitable leathers or plastics or rubber, or a rubber substitute, with or without textile layers or reinforcements. In the form of Figures 5 and 6 I illustrate a particularly advantageous structure in which interpenetrating loop ends form a cushion which receives and damps the impact of the moving mechanism along the spindle without causing a throw-back or elastic return. The nose A is preferably of a single piece, with or without washers 35, and should be of a relatively tough material to receive the impact with a minimum of wear. As will be clear from Figure 5, a substantial series of abutting layers of tough resistant material are thus provided. The remaining loops, with their interpenetrating ends, are spaced along the spindle and are compressed together by the movement against the nose A of a moving part of the textile machinery. Whereas the member 1 indicates an applicator spindle, it will be understood that the drawings illustrate the relative position or disposition of the parts on the spindle of the textile machine.

I claim:

1. In a spindle bumper structure and impact nose therefor, a multi-piece bumper body including a plurality of bent straps arranged in abutting relationship, said straps having each a pair of free ends, the free ends of the straps being apertured to receive a spindle, and being arranged in a plurality of abutting U's, and an impact nose abutting the outside free end of one of the bent straps, said impact nose including a unitary strap formed into a flattened spiral with a spindle receiving aperture passing therethrough.

2. The structure of claim 1 characterized in that all the bends of the flattened spiral abut.

3. The structure of claim 1 characterized in that all the bends of the flattened spiral abut, and in the inclusion of one or more washers within said spiral and abutting adjacent parts of the spiral.

4. The structure of claim 1 characterized in that the unitary strap has a free end extending between the free ends of the bent strap against which the impact nose abuts.

5. In a spindle bumper structure, a multi-piece bumper including a plurality of bent straps arranged in abutting relationship, each such strap having a pair of free ends, and an intermediate curvilinear portion, each such strap having at least one end disposed adjacent the curvilinear portion of an adjacent strap, the free ends of all of said straps being apertured and being thereby adapted to be applied to a spindle, an impact nose abutting the outside free end of the terminal strap of said spindle bumper structure, said nose including a unitary strap formed into a flattened spiral of abutting bends, with a spindle-receiving aperture passing therethrough.

6. In a spindle bumper structure, a multi-piece bumper including a plurality of bent straps arranged in abutting relationship, each such strap having a pair of free ends, and an intermediate curvilinear portion, each such strap having at least one end disposed adjacent the curvilinear portion of an adjacent strap, the free ends of all of said straps being apertured and being thereby adapted to be applied to a spindle, an impact nose abutting the outside free end of the terminal strap of said spindle bumper structure, said nose including a unitary strap formed into a flattened spiral of abutting ends with a spindle receiving aperture passing therethrough, said flattened spiral having an end portion extending between the free ends of the bent strap against which the impact nose abuts, said end being apertured to be applied to the spindle.
